UNITED STATES PATENT OFFICE

105,654

DESIGN FOR A DRAPERY FABRIC OR SIMILAR ARTICLE

Elsie J. Das, Honolulu, Territory of Hawaii, assignor to Watumull Brothers, a firm composed of Jhamandus Watumull, Gobindram J. Watumull, and Ramchand Watumull, and doing business as East India Store, at Honolulu, Territory of Hawaii

Application January 4, 1937, Serial No. 66,880

Term of patent 3½ years

To all whom it may concern:

Be it known that I, Elsie J. Das, a citizen of the United States, residing at Honolulu, in the county of Honolulu, Territory of Hawaii, have invented a new, original, and ornamental Design for a Drapery Fabric or Similar Article, of which the following is a specification, reference being had to the accompanying drawing, forming part thereof.

In the accompanying drawing:—

The figure is a face view of the full width of a drapery fabric or similar article, showing my new design.

I claim:

The ornamental design for a drapery fabric or similar article, substantially as shown.

ELsie J. Das.
